UNITED STATES PATENT OFFICE

HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS

DRESSING DEVICE FOR GRINDING ELEMENTS

Application filed April 20, 1928. Serial No. 271,432.

The invention relates generally to dressing devices for rotary grinding elements, the general object of the invention being to provide a new and improved mounting and actuating means for tools or dressing elements whereby a rotary grinding element, or a plurality thereof, may be readily and accurately dressed to a predetermined contour. 55

A further object is to provide such a device having novel means for accurately controlling the movement of the dressing elements.

Another object is to provide such a device embodying novel means for adjusting the dressing elements thereon.

Another object is to provide an improved dressing device of this character having a carrier for the dressing elements which has a minimum of static frictional resistance to movement so that the feeding movement of the carrier may be accomplished in an extremely uniform manner which obviates the jerking which ordinarily is present when one member is moved slowly over another.

A further object is to provide a dressing tool carrier having a plurality of dressing tools pivotally mounted thereon and embodying resilient adjustable means whereby a yielding pressure may be applied to all of the tools to press the tools into firm contact with the gage surfaces of a template.

Other objects and advantages will become apparent from the following description and from the accompanying drawings in which:

Figure 1 is a plan view partially in section of a mechanism embodying the preferred form of the invention.

Fig. 2 is a perspective view of the tool carrier with parts broken away in order to show the interior construction thereof.

Fig. 3 is a perspective view of a dressing tool.

Figs. 4 and 5 are fragmental vertical sections taken along the lines 4-4 and 5-5 respectively in Fig. 1.

Fig. 6 is a plan view of the template used in adjusting the dressing tools.

While there is shown in the drawings and will herein be described in detail the preferred embodiment of the invention as ap-

plied to a multiple dressing device for grinding elements, it is to be understood that it is not intended thereby to limit the invention to the specific form disclosed, the aim being to cover all modifications and alternative constructions falling within the spirit and scope of the invention as expressed in the appended claims.

In the preferred embodiment of the invention illustrated herein a main frame 9 may represent the bed or base of a grinding machine which is provided with a work supporting table 10 and has a rotatable arbor 11 adapted to support the grinding element or elements 12 which are to be dressed. In its present form the invention contemplates that the arbor 11 is fixed against longitudinal movement and that the grinding elements 12 are secured in axially spaced relation thereon by means such as sleeves 13 and washers 14. 60 65 70

The invention is well adapted for tool holders of the multiple type and as illustrated in the drawings, a plurality of grinding elements are arranged to be dressed by 75 means of a plurality of tools which are movable in unison in duplicate paths relatively to the grinding elements. To this end the table 10, upon which the dressing device is mounted in preferably slidably transversely 80 of the arbor 11 so as to allow the dressing device as a whole to be moved into and out of an operative relation to the grinding elements. In the present instance the table 10 is provided with ways 16 formed thereon and arranged to engage longitudinal guides 85

17 (Fig. 5) on the bed 9. A base 18 is stationarily mounted on the table 10. Thus it will be seen that the table 10 and the base 18 may be moved along guides 17 into the desired 90 proximate relation with the grinding elements. The table may be fixed in such adjusted position relative to the frame 9 by any preferred means (not shown).

The invention provides a movable carrier 95 for supporting a plurality of tool holders 21 together with means for mounting said holders adjustably upon the carrier and mechanism for actuating the carrier arranged to move the tool holders through the desired 100

paths. In the present instance this tool carrier is designated 22 and is preferably mounted on the base 18 for movement in a horizontal plane so that the tool holders 21 carried thereby will be moved in a plane which is radial with respect to all of the grinding elements 12.

In order that the dressing tools may be fed across the cutting elements and caused to dress the same at a uniform feeding speed a mounting is provided for the carrier 22 which practically eliminates all static frictional resistance of the carrier 22 on its support. The provision of such means serves substantially to eliminate the jerking or uneven feeding of the carrier which would result from the application of a relatively large force to overcome the static frictional resistance of the device when moving the carrier at a slow rate. To this end the carrier 22, which is of substantially rectangular form, is shown mounted upon bearings formed by a plurality of balls 25 (Fig. 1) positioned in upwardly extending recesses 26 formed in the bottom of the carrier 22, the balls 25 being of smaller diameter than the recess 26 and adapted to roll between a pair of parallel hard steel plates 27, 27^a (Fig. 4) mounted on the top of the base 18 and in the recesses 26 respectively. The carrier is guided in its movement to conform with the shape desired upon the grinding elements as described hereinafter.

The tool holders 21 are preferably mounted adjustably upon the carrier 22 in properly spaced relation and mechanism provided for adjusting the holders simultaneously and for locking the holders in their adjusted positions. Thus, as illustrated in the drawings the carrier 22 is recessed along its upper edge adjacent the arbor 11 so as to provide a flat horizontal surface or ledge 30 extending across the carrier upon which the tool holders 21 may rest. The ends of the tool holders 21 project beyond the forward edge of the carrier 22 and are herein illustrated as equipped with dressing tools or diamonds 31 for dressing the wheels 12 to form.

For the purpose of securing the tool holders 21 in position on the carrier 22, so that the tools 31 may be adjusted laterally of the grinding elements, the holders are pivotally mounted intermediate their ends on a plurality of vertical pivot pins or bolts 37 which are spaced apart equally with the elements 12 to be dressed. A bar 35 (Fig. 2) is placed above the tools and extending along the front edge of the carrier and provided with a plurality of vertical bores 36 formed therein at intervals equal to the desired distance between the dressing points 31.

The bolts 37 extend downwardly through the bores 36, through bores 39 formed in each tooth holder 21 intermediate its ends, and into engagement with the body of the carrier.

Thus the tool holders are movably secured to the carrier so that the tools may be adjusted laterally of the carrier in a horizontal plane. When the carrier 22 is to be used to hold a less number of tool holders 21 than the number for which it was designed, a plurality of dummy tool holders 21^a may be provided which do not extend beyond the front face of the carrier.

To lock the tool holders 21 in position after they have been adjusted, clamping means is provided which, when applied, has no tendency to disturb the accurate adjustment of the tool holders. In the preferred form illustrated this means comprises a pressure plate 40 interposed between the upper surface of the tool holders and the lower surface of the bar 35. This plate is arranged to be pressed against the tool holders by means of a plurality of pairs of plungers 41 which extend through vertical bores 42 in the bar 35 in front and in back of the pivot bolts 37 and into contact with the pressure plate immediately above the holders and which are adapted to be pressed downwardly by screws 43 mounted in a cover plate 44 which extends over the bar 35.

The holders are preferably arranged so that normally the tools will be urged yielding toward the grinding elements when the pressure plate 40 is released. Thus the tools 31 may be adjusted by means of a template 47 as illustrated in Fig. 6, which template is provided with properly spaced gage surfaces 48, one for each tool and has dowel pins 47^a arranged to fit into holes 47^b on the carrier to position the template accurately thereon.

To urge the dressing points 31 into contact with the gage surfaces 48 of the template, and thus to cooperate with the template in adjusting the tool holders, a plurality of resilient rods or springs 60 are arranged to engage the rear ends of the tool holders. In the preferred form illustrated herein these rods are mounted within the body of the carrier 22 on a bar 50 which extends along and is slidable transversely of the rear ends of the tool holders 21 and is arranged to be operated from the exterior of the carrier for the purpose of adjusting simultaneously the tension of the spring rods. The bar 50 is mounted in a groove 51 formed in the face of a member 52 which is positioned to the rear of the bar 35.

In the exemplary form of the invention the resilient rods 60 are secured at one end to the front face of the bar 50 and with their free ends extending downwardly therefrom into contact with knife edges 61 formed on one side of the rear ends of the tool holders 21. The rods 60 are herein mounted on the bar 50 by means of bolts 62 which extend through suitable bores formed in the bar 50 and to the heads of which the rods are suitably anchored. Preferably the rods 60 extend upwardly from the bolt heads and over pins 63

secured to the bar 50 and then downwardly to engage the tool holders 21, thus providing for a more secure mounting and greater resiliency of the rods. The tension of the

5 spring rods may be varied by moving the bar 50 transversely of the ends of the tool holders. To permit of such adjustment a square headed screw member 55 is threaded into the end of the bar 50 and is fixed against longitudinal movement by a collar 56 thereon which is positioned between an end plate 57 and the ends of the members 35 and 52. The squared end of the screw 55 extends through the end plate 57 to permit manipulation from 10 the exterior of the carrier and may be provided with a lock nut 58 so that the bar 50 may be clamped in its adjusted position.

For the purpose of excluding dirt and refuse from the inner parts of the carrier, 15 a shield 65 is provided which surrounds each of the tool holders 21 and extends entirely over the opening left in the face 32 of the carrier. In the form illustrated the shield 65 is made from sheet rubber and fits snugly 20 about the tool holders 21 and into notches 66 (Fig. 3) formed in the corners thereof and is secured to the face 32 of the carrier 22 by means of a clamping frame 67 secured to the carrier by means of screws 68.

25 The tool carrier 22, as mentioned hereinbefore, is movably mounted on the base 18 by means of the balls 25 which practically eliminate static friction of the carrier on the base. It is contemplated that equally frictionless means will be provided to actuate and control the carrier to move the tools through the desired path so as to dress the grinding elements 12 accurately to the desired contour. The present embodiment of 30 the invention contemplates the actuation and movement of the carrier in two directions which are at right angles to each other and the control of such movement in the two directions by two separate means inter-related 35 so as definitely to determine the relative amounts of movement in the two directions and thereby control the resultant path of the carrier.

The actuating means for the carrier 22 preferably embodies yieldable means which 40 normally tends to retract the carrier from operative engagement with the grinding elements 12 and also means for positively moving the carrier into such operative engagement and against said yieldable means. Thus as illustrated herein a retractile coil spring 70 is secured at one end to the carrier 22 and extends rearwardly diagonally of the base 18 (Fig. 2) and is secured at the other end to 45 an upstanding rear wall 71 which is secured along the top rear edge of the base 18 as by means of screws 72. Due to the angular positioning of the spring 70, the carrier 22 is normally urged rearwardly away from the 50 grinding elements 12 and also transversely

of the base, away from the angular faces of the elements 12 and into constant engagement with the guiding and actuating means now to be described.

The means for moving the carrier 22 to 55 overcome the spring 70 and move the carrier toward the grinding elements 12 preferably embodies rolling contacts. As herein illustrated a cam carriage 75 is mounted on the base 18 between the rear wall 71 and the rear face of the carrier 22 for sliding movement transversely of the base and inclined cam blocks 85 secured to this carriage are arranged opposite to counter-positioned similar blocks 86 secured to the carrier 22. The pairs of opposing inclined surfaces of these cam blocks form raceways for balls 87 positioned therebetween.

The cam carriage 75 is preferably of T-shaped cross-section and is mounted in a forwardly opening slot 76 (Fig. 4) formed on the front face of the wall 71 and is retained therein by means of a guide bar 78 of L-shaped cross section secured to the overhanging portion 77 of the wall 71, and a 60 guide bar 80 which is secured to the upper surface of the base 18. To provide for accurate adjustment of the cam carriage in the slot a pair of taper gibs 82 are preferably interposed between the guide bars 78 and 80 and the front faces of the carriage 75. These 65 taper gibs 82 may be provided with suitable adjusting screw devices 83. Thus the cam carriage 75 is arranged for movement along an accurate, unvarying path transversely of 70 the base 18.

The cam blocks 85 and 86 are secured to the cam carriage 75 and tool carrier 22 respectively by means of screws 88 so as to be readily removable therefrom. The cam surfaces on opposite cam blocks 85 and 86 are 75 preferably parallel to each other and have side walls 89 formed thereon for the purpose of supporting the balls 87 in position. Thus when the cam carriage 75 is moved transversely of the base 18, the cams 85 through the medium of the balls 87, cause the carrier 22 to move longitudinally of the base, and, in case the inclined cam surfaces are straight and parallel, the amount of longitudinal 80 movement of the carrier 22 will be proportional to the amount of transverse movement of the cam carriage 75.

Because of the diagonal positioning of the spring 70 the carrier 22 is constantly urged 85 transversely of the base 18 and means is provided to control movement under this impulse according to the amount of longitudinal movement of the carrier. This means as herein shown comprises opposing guide or 90 control cam blocks 90 and 91 secured respectively to one side of the carrier 22 and to an adjustable slide 91a (Fig. 1). The cam blocks 95 are preferably provided with parallel grooved surfaces 92 and 93 between which a 100

ball 94 is positioned to provide a rolling bearing therebetween. The form of the two cam surfaces 92 and 93 is such that when the carrier 22 is moved longitudinally of the base 18 toward the work, the carrier will be moved in a path such as will provide the desired contour on the grinding elements 12, the spring 70 serving to hold the carrier yieldingly against the actuating and control cams.

To provide a greater range of transverse carrier movement and the use of a simpler form of grooved control cam when it is desired to dress the grinding elements to more complex contours, the cam block 91 is preferably mounted for movement longitudinally of the base 18 under the control of the cam carriage 75. To this end the slide 91^a to which the cam block 91 is secured, rests upon the upper surface of the base 18 for sliding movement thereon (Fig. 5). A side wall 95 secured upon the base has a plurality of grooved ball retainers 99 secured thereto in which retainers balls 101 are positioned arranged to provide a rolling abutment for the slide 91^a. Preferably hardened steel plates 102 are secured to the slide to engage the balls 101.

The slide 91^a is normally urged longitudinally along and against the side wall 95 by means of a diagonally positioned contractile coil spring 98, the ends of which are fastened to the slide 91^a and the wall 95 respectively (Fig. 1). A laterally extending portion 103 of the wall is preferably arranged so as to project over the top of the slide 91^a to guide the slide in its sliding movement on the base 18.

At the rear end of the slide 91^a a roller 106 is mounted upon a vertical pin 106 in position to engage and roll upon a cam surface 107 formed upon a block 108 which is mounted on the cam carriage 75. Thus when the cam carriage is moved transversely of the base 18, the cam surface 93 will be moved longitudinally of the base in accordance with the contour of the cam surface 107 and the amount of movement of the cam carriage and will thus serve to vary the movement of the carrier 22 which would ordinarily be caused by the cam 93.

This arrangement makes possible the use of more simple and economically formed cams for guiding the tools than would be permissible to produce complicated movements of the tool carriage if but a single control cam were used.

Any suitable means may be provided for conveniently actuating the cam carriage 75 back and forth across the base. As herein illustrated this means comprises a link 110 which is pivotally connected at one end to the front face of the cam carriage 75 by a bolt 111 (Fig. 5) and at the other end to a crank arm 112 by a pivot pin 113. The crank arm 112 is preferably fixed upon a rock shaft 114

which is in turn rotatably mounted on the table 10, any preferred manual or power means (not shown) being used to rock the shaft 114 and thus reciprocate the cam carriage 75.

Thus when it is desired to dress a plurality of grinding elements 12, the tool holders may be readily and accurately adjusted by reason of the resilient pressure means embodied in the carrier for urging the holders into engagement with a template of simple form, and the holders may then be secured in their adjusted positions by means which is accessible exteriorly of the carrier. The entire dressing device may then be moved bodily along the ways 17 into proximity to the grinding elements, in which position the carrier 22 and the dressing tools thereon may be moved back and forth along the desired path by reciprocating the cam carriage 75. Since rolling contacts are provided between the carrier and its supporting and actuating means, the static friction of the movable carrier on its support is reduced to a minimum and the movement of the carrier may be readily accomplished at a uniform feeding speed. The provision of the cam 107 for varying the effectiveness of the cam 93, serves to simplify the other cams when it is desired to give a complicated movement to the dressing tools 31.

From the foregoing it will be apparent that the invention provides means whereby a plurality of dressing tools may be easily actuated and their path of movement accurately controlled so as to dress a plurality of grinding elements to a predetermined contour.

It will also be apparent that the invention provides novel means for readily securing an accurate adjustment of the dressing tools in the tool carrier together with an effective clamping means for securing the tool holders in their adjusted positions.

I claim as my invention:

1. In a device of the class described, a base having upstanding side and rear walls, a tool carrier movably mounted on said base adjacent said walls, a cam carriage mounted on said base for movement transversely of said base along said rear wall, cam means on said carriage arranged when said carriage is moved in one direction to engage and move said carrier longitudinally of said base, spring means connecting said carrier and said rear wall operable to oppose such movement of the carrier, a control slide mounted adjacent said side wall for movement longitudinally of said base along said wall, cam means on said slide engaging said carrier and operable to control the transverse movement of said carrier according to the relative longitudinal movement of said slide and said carrier, spring means connecting said slide and said side wall, and cam means on said cam carriage arranged to cooperate with said spring to actuate and control the movement of said slide.

- longitudinally of said base in accordance with the transverse movement of said carriage.
2. A device for dressing the peripheral edge of a rotating grinding element to a given contour, said device comprising a stationary base adapted to be mounted adjacent such a grinding element, a tool carrier movably mounted on said base, a dressing tool mounted on said carrier, and means for actuating and controlling the movement of said carrier to move said dressing tool to dress a grinding element to the desired contour, said means comprising a cam device mounted on the base for reciprocation transversely thereof and arranged when moved in one direction to actuate and move said carrier longitudinally of said base, spring means operable to oppose such movement of the carrier and to return said carrier when the cam device is moved in an opposite direction, and a second cam device mounted on said base to engage said carrier and to cooperate with said spring means to control transverse movement of said carrier.
3. In a device of the class described, a base, a tool carrier movably mounted thereon, a cam carriage mounted for reciprocatory movement transversely of said base adjacent said carrier, cam means on said cam carriage engaging the carrier so as to cause movement of said carrier longitudinally of said base when said cam carriage is moved along its path, and means operable to control the transverse movement of said carrier according to its longitudinal movement on said base.
4. A device of the character described, comprising in combination, a base, a tool carrier movably mounted thereon, means for reciprocating said carrier longitudinally of said base, a cam slide mounted on said base engaging said carrier and operable during said longitudinal movement to govern transverse movement of said carrier on said base, and a second means operable by said first means to control the position of said cam slide whereby to control the effectiveness of said cam slide.
5. A dressing device for grinding elements comprising a base, a dressing tool, a tool carrier therefor mounted on said base for limited planar movement thereon, a cam movable in one direction to impart movement to said carrier in a direction at an angle to the direction of movement of said cam, a second cam surface mounted on the base engaging said carrier and operable when said carrier is moved by said first cam to permit movement of said carrier in a direction parallel to the path of movement of said first cam.
6. A tool support comprising, in combination, a base, a tool, a tool carrier therefor, means to actuate and control the movement of said carrier in one direction, a second means for controlling movement of said carrier in a second direction angularly disposed with respect to said first direction according to the

movement of said carrier in said first direction, and a third means associated with said first mentioned means for varying the controlling effect of said second mentioned means.

7. In a device for adjustably holding a plurality of tools, a body, a plurality of tools pivotally mounted thereon, a bar slidably mounted on said body adjacent said tools, a plurality of resilient members mounted on said bar, one engaging each of said tools to impart a yielding rotative force thereto, and means for longitudinally moving said bar whereby to vary said yielding force.

8. The combination of a plurality of dressing tool holders having dressing points mounted near one end, a part to which each of the tools is pivoted, said tools being adapted to be adjusted by means of a template having a plurality of gage surfaces to engage said dressing points so as to properly space the same, means for securing said tools in adjusted position, a member mounted on said part for adjustment relative thereto, and a plurality of spring devices mounted on said member and engaging said dressing tools whereby said tools may be moved about their respective pivots and the dressing points firmly held in contact with said gage surfaces while the tools are being secured in their adjusted positions.

9. A device for dressing the peripheral edge of a rotating grinding element to a given contour, said device comprising a stationary base adapted to be mounted adjacent such a grinding element, a carrier member movably mounted on said base, a dressing tool mounted on said carrier member, and means for actuating and controlling movement of said carrier member to move said dressing tool to dress a grinding element to the desired contour, said means comprising a cam member mounted on the base for reciprocation transversely thereof and arranged when moved in one direction to actuate and move said carrier member longitudinally of said base, spring means operable to oppose such movement of the carrier member and to return the carrier member when the cam member is moved in an opposite direction, a second cam device mounted on said base to engage said carrier member and to cooperate with said spring means to control transverse movement of said carrier member, and means acting between said second cam device and one of said members operable by movement of said last mentioned member to vary the controlling effect of said second cam device.

In testimony whereof, I have hereunto affixed my signature.

HOWARD D. COLMAN.
